UNITED STATES PATENT OFFICE.

ROBERT COSMOS ELLRICH, OF SOUTHBURY, CONNECTICUT, ASSIGNOR TO
THE PECK, STOW & WILCOX COMPANY, OF SAME PLACE.

DESIGN FOR A WRENCH-FRAME.

SPECIFICATION forming part of Design No. 28,512, dated April 26, 1898.

Application filed December 23, 1896. Serial No. 616,816. Term of patent 7 years.

To all whom it may concern:

Be it known that I, ROBERT COSMOS ELLRICH, a citizen of the United States, residing at Southbury, in the county of Hartford and State of Connecticut, have invented and produced a new and original Design for a Wrench-Frame, of which the following is a specification, reference being had to the accompanying drawings, in which—

Figure 1 is a side elevation of a wrench-frame showing my design; and Fig. 2 is an edge view thereof, showing the upper edge of Fig. 1.

The leading feature of my design is the longitudinal slot shown in Fig. 2 and the broad flat sides shown in Fig. 1.

A designates the body of the frame, which is in the general form of a bar with mainly parallel straight edges and a rounded end 3. Near the middle portion at the upper edge, in the position shown, there is a row of teeth 4, of a character often called "dental work" in architectural designs. At the other end of the body and projecting from the same edge as that having the teeth 4 is a tapering projection 5, which, with the body, forms an L-shaped figure. The adjoining edges of the projection 5 and body A on their inner edge stand at right angles to each other, as shown.

The outer end 6 of the projection 5 is also 30 straight and at right angles to its inner edge. From the outer end 6 the outer edge of the projection 5 extends on a straight but inclined line to a point nearly in the plane of the inner or toothed edge of the body and then 35 curves around, as at 7, to meet the under straight edge, in harmony with the rounded end 3. The broad sides of the body A are flat and smooth, without slots, grooves, or openings. The corners are mostly right angular excepting on that portion of the body that extends to the right of the teeth 4, and on this portion the corners are slightly rounded. As shown in edge view, Fig. 2, there is a slot 40 or opening 8, of the form shown, extending 45 from the projection 5 to a little beyond the end of the row of teeth 4, the said slot being nearly equal in width to the thickness of the metal in the body on either side of the said slot. 50

What I claim is—

The design for a wrench-frame herein shown and described.

ROBERT COSMOS ELLRICH.
